UNITED STATES PATENT OFFICE.

ALBERT F. DAUM, OF PITTSBURGH, PENNSYLVANIA.

FUSE-PLUG.

1,367,803.

Specification of Letters Patent.

Patented Feb. 8, 1921.

Application filed November 24, 1919. Serial No. 340,307.

To all whom it may concern:

Be it known that I, ALBERT F. DAUM, a citizen of the United States, residing at Pittsburgh, in the county of Allegheny and State of Pennsylvania, have invented certain new and useful Improvements in Fuse-Plugs, of which the following is a specification.

This invention relates to improvements in fuse plugs, pertaining more particularly to plugs of the general type disclosed in my companion application filed September 12, 1914, Serial No. 861,414, viz.: plugs in which the fusible element is extended through the closed end of the plug casing and forms a direct contact with a terminal of the socket.

In the companion application, the opposite end terminal of the socket contacts with a ferrule which, in turn, is connected to a rigid connection or bracket which leads into the casing, the fusible element,—in strip form—being connected to the bracket within the casing. While the plug of the companion application is of a form to decrease the cost of manufacture, by dispensing with the necessity of a special contact at the closed end of the plug, the cost of the ferrule and of the connection or bracket form material items in the cost of manufacture, owing to the character of material required and the particular forms necessary for the purpose.

The present invention is designed to still further reduce the cost of manufacture—and at the same time preserve the feature of ready renewal of fusible elements—by substituting the fusible element itself for the ferrule and connection or bracket of the earlier structure, both terminals of the socket having direct connection with the fusible element.

In addition, the cost may be further reduced by substituting a simple and less expensive structure for the removable cap, the plug thus being produced mainly of insulating material, such for instance as porcelain, glass, fiber, etc.

To these and other ends, therefore, the nature of which will be readily understood as the invention is hereinafter disclosed, said invention consists in the improved construction and combination of parts herein-after more fully described, illustrated in the accompanying drawings, and more particularly pointed out in the appended claims.

In the accompanying drawings, in which

similar reference characters indicate similar parts in each of the views,—

Figure 1 is a vertical sectional view taken through one form of plug, the latter being seated in a complementary socket, also shown in section.

Fig. 2 is a sectional view showing a modified form of plug.

Fig. 3 is a bottom plan view of the plug of Fig. 2.

Fig. 4 is a view, partly in section and partly in elevation, showing a further modification.

Fig. 5 is a top plan view of the plug of Fig. 4.

Fig. 6 is a further modification shown in longitudinal section.

Fig. 7 is a still further modification, shown in section.

Fig. 8 is a top plan view of the structure of Fig. 7.

Fig. 9 is a sectional view of another modification.

Fig. 10 is a top plan view of the same.

In the drawings, 15 designates the hollow casing, formed of insulating material, such for instance as porcelain, glass, fiber, etc., the casing having a closed bottom 15^a with a projecting teat or projection 15^b on its outer face, said teat forming a seat for one terminal end of the fusible element 16—preferably in strip form—the closed end having a slot 15^c for the passage of the element in reaching the seat.

The exterior of the casing is preferably of the two-diameter type, the portion of smaller diameter having the usual coarse threads 15^d, with the possible exception of a portion 15^e forming a depression leading from a longitudinal slot 15^f formed in the portion of larger diameter, depression 15^e terminating above the lower threads of portion 15^d, these latter threads being preferably substantially continuous, excepting as presently described.

The upper portion of the wall of the casing between slot 15^f and the interior of the casing, is omitted—the depth of the wall depression thus formed varying, as indicated in Figs. 1, 6 and 7, for instance, the bottom of this wall depression forming a ledge over which the fusible element is led.

The fusible element has one terminal end seated on the face of teat or projection 15^b, and may, as in the companion application and as shown in Fig. 6, extend into a

depression on the closed end; however, I preferably provide an additional slot 15^s in the closed bottom spaced from slot 15^e the distance of the teat or projection, and 5 through which the free end of the element is led back into the interior of the casing and bent over as shown, for instance, in Fig. 1. This latter arrangement is preferred, 10 since it eliminates any possibility of the end of a blown strip dropping off of the plug when the latter is removed for renewal of the fuse, thus preventing the possibility of a dropped element portion bridging the terminals of the socket. Obviously, either slot 15^e or 15^s may form the slot through which 15 the free end is passed, the other slot forming the passageway for the strip which leads into the interior.

The element extends through slot 15^e—or 20 slot 15^s as the case may be—through the interior of the casing, over said ledge and then through slot 15^f along depression 15^e and over on to the threaded portion 15^d, as in Fig. 1, or into a recess 15^g having a recessed 25 offset 15^h, as in other figures. In either case, a portion of the fusible element overlies the unbroken threaded portion 15^d, and hence is in direct contact with the threaded contact 17^a of the socket 17, when the plug is 30 screwed or threaded into the socket, the opposite terminal end of the fusible element—which overlies the teat or projection 15^b—contacting with the other terminal 17^b of the socket.

35 In each instance, therefore, opposite end portions of the fusible element—both external of the plug casing—are in contact with the separate terminals of the socket, and are so located as to practically prevent 40 the formation of an arc between these terminals. This leaves the interior of casing 15 to receive the intermediate portion of the fusible element, and as the latter may and 45 preferably is formed with a weakened portion in this interior length of the element, it will be readily understood that "blowing" of the element will take place within the interior of the casing, the contacting ends being less likely to "blow" by reason of 50 the metallic contact with the socket terminals. Obviously, threaded portion 15^d is threaded directly to the socket, the usual ferrule being omitted, thus decreasing cost of production in this respect.

55 Various forms of closure for the casing may be employed, each including the usual mica element 18 or its equivalent.

In Fig. 1 I have shown the usual ferrule 19 threaded to the portion of the casing of 60 larger diameter, the ferrule overlying element 18. This ferrule may also be employed in the form shown in Fig. 2 or where this portion of the casing has a threaded exterior, the structure being such as to retain 65 element 18 in position overlying the bent

portion of the fusible element which extends over the ledge.

In Figs. 4 and 5 I have shown the ferrule substituted by a resilient strip 20 bent to form legs 20^a which extend through longitudinal openings 15^m of the casing, the legs 20^a having feet 20^b which extend beneath a shoulder exterior of the casing, this strip overlying the mica element, and being readily removed by springing the legs inwardly 75 to bring the feet into alignment with openings 15^m. In Fig. 6 I show this arrangement applied to a formation in which the ledge is depressed, thus locating the mica element within the casing. 80

In Figs. 9 and 10 I show a variation of this latter structure, the openings 15^m being omitted, the resilient strip being carried over the portion of the casing of larger diameter and having its feet bent inwardly 85 instead of outwardly, the feet passing beneath the shoulder formed at the junction of the two portions of the casing of different diameters. The legs of the strip may pass through external longitudinal grooves, if 90 desired.

Obviously, the tension of the strip of Fig. 4 will be exerted in directions opposite to that of Fig. 9.

In Figs. 7 and 8 the mica element is held 95 in position by a split washer 21 underlying lugs 15ⁿ formed on the casing.

As will be understood, the structures of Figs. 4 to 10 eliminate the necessity for employing the ferrule structure 19, reducing 100 the cost of manufacture accordingly. As a result, the use of metallic formations is reduced to a minimum, the major portion being the hollow casing and the fusible element. 105

As will be understood, the different views show various formations for illustrative purposes only. These may be arranged in any preferred way, as for instance the closed end arrangement of Fig. 6 may be employed with all forms, the strip of Fig. 10 may be used as shown in connection with the strip of Fig. 6, the outer end terminal may be as in Figs. 1 or 2, etc. 110

While I have herein shown and described 115 various ways in which my invention may be carried into effect, it will be readily understood that changes and modifications therein may be found desirable or essential in meeting the various requirements of use, and I 120 desire to be understood as reserving the right to make any and all such changes or modifications as may be found desirable or necessary, in so far as the same may fall within the spirit and scope of the invention 125 as expressed in the accompanying claims when broadly construed.

Having thus described my invention, what I claim as new is:

1. A renewable fuse plug comprising a 130

hollow casing of the cup type, said casing having an external seating face for a fusible element positioned to locate predetermined portions of the element in direct contact with the terminals of a complementary socket and an intermediate portion of the element within the interior of the casing.

2. In a renewable fuse plug, a hollow casing having a closed end and an external seat for an end portion of a fusible element, said casing having a threaded portion adapted to thread into a complementary socket, said casing also having a longitudinal opening and a depression leading to said threaded portion to constitute a portion of the threaded portion as a seat for the opposite end portion of the element to permit direct contact of the element and a socket terminal.

3. A fuse plug of the type of claim 2 characterized in that the threaded portion of the casing is provided with a recess located beyond the threaded portion and into which the end of the fusible element may extend.

4. A fuse plug of the type of claim 1 characterized in that the hollow casing is provided with a ledge over which the fusible element is led, an insulating element closing the open end of the casing and overlying said ledge and the fusible element, and means for removably securing the insulating element in position.

5. In a fuse plug adapted to engage a socket, a hollow casing having an open end and formed to receive a fusible element with the latter extending both exteriorly and interiorly of a casing wall, said casing having longitudinal openings extending from the plane of said open end, and also having a shoulder positioned to be exposed when the plug is seated within its socket, an insulating element for closing said open end, and means for removably securing said insulating element in position, said means comprising a strip-like member overlying said in-

sulating element and having portions adapted to traverse said openings and removably engage such shoulder.

6. In a fuse plug adapted to engage a socket, a hollow casing having an open end and formed to receive a fusible element with the latter extending both exteriorly and interiorly of a casing wall, said casing having a shoulder positioned to be exposed when the plug is seated within its socket, an insulating element for closing said open end, and a resilient member overlying said insulating element and removably engaging said shoulder, whereby said insulating element will be removably maintained in position.

7. The combination with a socket having terminals, of a fuse plug comprising a hollow casing of the cup-type, and a fusible element, said casing having external seats for the element in direct opposition to said terminals to provide direct contact of the element with the terminals, said casing having a formation to permit an intermediate portion of the element to traverse the interior of the casing.

8. A plug fuse comprising a hollow casing having a closed end and formed to provide independent external seats in opposition to the terminals of a complementary socket, and a fusible element having a length to traverse the interior of the casing and extend in overlying relation to said seats, said closed end of the casing being formed to permit the element to pass therethrough into seating position and reenter the casing interior to permit the element end to be supported against dropping in the presence of a "blown" element.

9. A fuse plug of the type of claim 8 characterized in that the casing is provided with a recess beyond another seat to anchor the opposite end of the element in its seat overlying position.

ALBERT F. DAUM.
